UNITED STATES PATENT OFFICE.

STEPHEN E. ODELL AND FRANK L. CLIFT, OF BELLINGHAM, WASHINGTON.

MINING MACHINERY.

1,413,289.

Specification of Letters Patent. Patented Apr. 18, 1922.

Application filed July 25, 1919. Serial No. 313,362.

To all whom it may concern:

Be it known that we, STEPHEN E. ODELL and FRANK L. CLIFT, citizens of the United States, residing at Bellingham, in the county 5 of Whatcom and State of Washington, have invented certain new and useful Improvements in Mining Machinery; and we do hereby declare the following to be a full, clear, and exact description of the invention, such as will enable others skilled in 10 the art to which it appertains to make and use the same.

This invention relates to mining machinery and has for an object to provide a machine and method combining in its operation the features and results of placer mining and the amalgamation process.

A further object of the invention is to provide a machine whereby the ores or mineral 20 bearing earth may be broken up into finer particles and the valuable metals separated and conserved and the waste matter eliminated, either without water or with a water supply in the nature of a running stream or 25 a still body of water.

A further object of the invention is to provide a light easily transported and cheaply organized structure adaptable for prospector's use for placer mining, and 30 amalgamation process in quartz mill work.

With these and other objects in view the device comprises certain novel combinations and arrangements of parts as will be herein-after more fully described and claimed.

35 In the drawings,

Figure 1 is a view of the structure partly submerged in water showing the housing and a part of the rotating pan in diametrical section and the supporting members in 40 side elevation.

Figure 2 is a view in section of the modification of one of the parts.

Figure 3 is a top plan view with the driving shafts in transverse section.

45 Figure 4 is a view of one type of rotating pan.

Figure 5 is a fragmentary view in section of another type of rotating pan.

Figure 6 is a fragmentary view in section of another type of rotating pan.

Figure 7 is a view of the amalgam pan converted into a retort.

Figure 8 is a fragmentary sectional view of another type of rotating pan.

55 Figure 9 is a fragmentary sectional view of another type of rotating pan.

Like characters of reference indicate corresponding parts throughout the several views.

The improved mining implement which 60 forms the subject matter of the present application comprises a foot or base 1, above which rises a supporting standard or shaft 2 with a set screw 3 for regulating the elevation of the shaft 2.

Upon the upper end of the supporting shaft 2 a hollow shaft 4 is provided preferably with the ball race and balls 5 as indicated at Figure 1 so that the hollow shaft 4 may rotate upon the shaft 2.

70 For the purpose of driving the hollow shaft 4 a drive of any approved type as for instance the belt 6 from any convenient source of power is employed.

About the base of the hollow shaft 4 a 75 cone is provided having members 7 spaced apart forming openings through which water is received replacing that removed by centrifugal force, thus forming a constant current.

To the base of the cone 7, a disc or pan 8 is secured in any approved manner as by the bolt 9. The disc 8 is provided with a spiral rib 10, the spiral being so positioned as to have a tendency to return the coarser 85 metals toward the center of the disc 8 and extends from near the center of the disc in its spiral whorls to approximately the edge of such disc. The disc 8 is provided with a central opening 11 registering with the opening 80 in the bottom of the cone forming an entrant opening for current of water.

About the central disc 8 a pan is erected, such pan being of various types according to the demands of the use and each or any of 95 said pans secured to the disc 8 by the bolt 12.

As shown in Figures 1 and 3, the pan 13 is slightly dished to correspond with the dishing of the disc 8 and is provided between the disc 8 and its periphery with ruffles 14. The 100 edge of the pan also provided with ruffles is turned up as shown up at 15 with the flange inwardly turned to form a groove or furrow the utility of which will be hereinafter more fully explained.

105 Instead of employing the pan as shown at 13, the type of pan shown at Figure 4 may be employed having a plurality of steps formed of inclined portions 16 and vertical portions 17. Within the outer steps a furrow 18 is formed with a furrow 19 at its upper and outer periphery. The utility of the

several furrows formed by the inturned flange or flanges 19 and the furrow 18 will be hereinafter more fully explained.

The type of pan shown at Figure 5 may 5 be substituted for either of the two just mentioned having inclined walls 20 for the several steps with vertical connecting walls 21 and grooves 23.

Also may be substituted the type of pan 10 shown at Figure 6 wherein the inclined walls 24 and 25 are at a lesser angle to the horizontal and no vertical walls are employed, employing however inturned flanges at 27 forming furrows the utility of which will be explained 15 in connection with the like furrows and flanges in the other types.

The type of pan shown at 28 may also be employed having one inclined wall 29 only with the furrow 30 formed therein and adjacent 20 its upper and outer periphery.

Also the type of pan shown at 31 may be substituted having only a vertical wall 32 with the furrow or groove 33 formed adjacent its upper and outer periphery.

Whatever the type of pan employed a 25 housing 34 is provided surrounding the pan, such housing being essentially a cylinder having about its lower edge an inwardly and upwardly turned spout 35 conforming to the circular formation of the housing but inclined toward one side and terminating in the discharge spout 35'. The material to be separated may be fed into the pan as through a trough 53.

The discharge spout 35 discharges into a 35 hopper 36 which is formed integral with or communicates with a pipe 36' all preferably supported from the base 1 and shaft 2 by the brackets 37 and 38, some of which also may 40 be employed to support the housing 34.

At its lower end the pipe 36' is rolled or turned to form a flange 39 and a shaft is extended axially through the pipe 36' and provided at a point corresponding substantially 45 with the lower end of the pipe 36' with propellers 41. The shaft is journaled in any approved manner as by the journalling spiders 42 which also serves to maintain the shaft 40 in proper relation to the pipe 36' irrespective 50 of other supporting elements.

A journalling spider 43 is also preferably provided at the hopper 36 and the shaft 40 is driven in any approved manner here shown as by means of a pulley 44 and belt 55 44' driven from the pulley 45 upon the hollow shaft 4.

Instead of employing the pipe 36' and its upturned flange 39, the pipe 36" may be employed having the return bend 46 as shown 60 at Figure 2.

Secured to the pipe 36 in any approved manner as by the spider 47 is a receptacle 48 such connecting being accomplished in any approved manner as by the bolt 49. This 65 receptacle 48 is intended to be removed from

connection with the pipe 36' and connected by a conical cover 50 with the pipe 51 which when immersed in water as indicated at Figure 7 and heat maintained under receptacle 48 serves as a retort for distilling off the 70 mercury, the use of which will be herein-after explained.

In operation the device is set in a container, stream or pool of water (not shown) until the bottom of pan 8 is covered so that 75 water will enter through hole 11 provided in the bottom for that purpose. Other means of supplying water to the center can of course be used. A pipe or nozzle 52 is provided for discharging such running water 80 from a suitable source not shown into the pan and an oil way 53 is provided for lubricating the rotating hollow shaft 4.

In operating the type of device shown particularly at Figure 1 the pan 13 is rotated by the application of power thereto and the material to be separated is placed near the center of the pan adjacent the cone. Water if available is admitted through the nozzle 52. The rotation of the pan is at 85 such a rate as to cause centrifugal force to act upon the content and serve to move it toward the periphery. The tendency of the water aside from centrifugal force is to flow by gravity toward the center of the pan and 90 even when centrifugal force is acting there-upon it serves as a retarding of the movement of the material in the bottom of the pan. The centrifugal force, however, causes the material together with the water to 100 move towards the periphery except that the larger and heavier particles of metal engage against the spiral 10 and by reason of the rotation of the pan in the proper direction and the retarding influence of the air 105 and the water upon the particles those particles are returned toward the center. The lighter particles and the water are carried by the centrifugal force toward the periphery of the pan over the riffles 14 into 110 engagement with peripheral groove formed at 15. The continued adding of material at the center of the pan and the continual action of the material moving by centrifugal force from the center of the pan serves to 115 introduce other and further material into the groove at the periphery. By this introduction of additional material at the periphery it is obvious that the heavier metallic particles by kinetic energy will displace the lighter particles in such peripheral groove and seek the outer circumference of the circle. When the groove has been filled to overflowing it is obvious that it will be the lighter particles which will be discharged over the periphery of the pan and into engagement with the housing 34 the 120 heavier particles of the metals remaining in the pan.

The material discharged over the pe- 130

riphery of the pan will be caught by the housing 34 and conducted by the trough 35 and spout 35' to the hopper 36 and by the pipe 36' to the receptacle 48, being agitated 5 in transit by the agitators or propellers 41.

It is intended to partially fill the receptacle 48 with mercury so that the material passing downwardly through the pipe 36' and propelled by the propellers 41 will pass 10 through the mercury content of the receptacle the values to be retained by such mercury by the well known amalgamation process.

When the activity of the mercury for 15 amalgamating with other metals has been exhausted to the desired degree the receptacle 48 is removed from its support and attached to the cover member 50 whereby a retort is formed and heat applied by which 20 such retort will distil the mercury over through the pipe 51.

In the type of pan shown at Figure 4 mercury is also introduced in the outer step in groove 18 and when the pan is rotated 25 such mercury will be moved by centrifugal force into the groove 19. The several grooves formed by the inturned flanges 19 will serve to retain heavier particles just as described in regard to the groove 15 as 30 shown at Figure 1 with the further utility that when the particles finally reach the outer groove they will be brought by kinetic energy into engagement with the mercury and the valuable metals being heavier than 35 the waste material will be the parts which are brought into engagement with the mercury and will be amalgamated thereby, discharging the waste material or the material containing but a small fraction of valuables 40 into engagement with the housing to be discharged into the receptacle 48 for again being acted upon by the mercury.

In the types of pans shown at Figures 5, 6, 8 and 9 no provision is made for the introduction of mercury into the pan but several 45 grooves are provided for the receipt and retention of the heavier particles in locations where the valuable metals are comparatively free serves the purpose admirably the amalgamation being resorted to only as a last 50 step for finally extracting the very last fraction of valuable metals from the waste materials.

In desert locations or locations where 55 water is not available the dry material is introduced directly into the hopper 36 and fed to the mercury in the receptacle 48 whereby the amalgamation process is carried out.

The return bend to the pipe 36" as shown 60 at Figure 2 may be substituted within the receptacle 48 and its upturned end covered by the mercury content of the receptacle

which also, of course, provides mercury within a mercury seal. It is impossible, therefore, for the material passing out of 65 the pipe 36" to escape into the receptacle 48 without passing through the mercury and to be acted upon thereby.

The explanation in regard to the several 70 pans already given will be understood in regard to the pans not specifically described.

Furthermore if running water is not available the machine may be partially immersed in still water and the process will be conducted exactly as above described. 75

The flange 39 turned outwardly and upwardly at the bottom of the pipe 36' constitutes a seal when it is immersed in mercury.

We claim:

1. The combination in an ore separating 80 pan of a centrifugal element, a counter-centrifugal element, a water supply operating centrifugally over the counter-centrifugal element, and a water supply operating counter-centrifugally over the centrifugal element. 85

2. The combination in an ore separating pan of a centrifugal element, comprising a series of concentric riffles arranged near the periphery, a counter-centrifugal element 90 comprising a spiral rib arranged centrally of the pan, a water supply from the center of the pan washing outwardly over said spiral rib, and a water supply at the periphery washing inwardly over said riffles. 95

3. The combination with a centrifugal separating pan, having a central opening for the inflow of water, of means formed in the bottom of said pan operating in opposition to centrifugal force adapted to return a portion of the material toward the center of the disc. 100

4. The combination with a centrifugal separating pan, of means formed at the periphery of the pan, adapted to intercept and retain the heavier material while the lighter material overflows, said pan being provided with a central opening for the inflow of water and means formed in said pan operating in opposition to centrifugal force 110 adapted to return a part of said material towards the center of disc.

5. The combination with a centrifugal separating pan, of means formed adjacent of its periphery for receiving and retaining 115 a body of amalgam-forming material and means formed in the pan adapted to operate in opposition to centrifugal force to return a part of said material toward the center of the disc. 120

In testimony whereof we affix our signatures.

STEPHEN E. ODELL.
FRANK L. CLIFT.
